(57) CLAIM

The ornamental design for a smartphone glove, as shown and described.

DESCRIPTION

FIG. 1 is an isometric view of a smartphone glove;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawing figures define the bounds of the claimed design and form no part thereof.
